CLAIM

We claim the ornamental design for a bead mold, as shown.

DESCRIPTION

FIG. 1 is a top plan view of the bead mold according to the claimed design;

FIG. 2 is a cross-sectional view thereof.

FIG. 3 is an enlarged view thereof.

FIG. 4 is a bottom plan view thereof.

FIG. 5 is a cross-sectional view thereof.

FIG. 6 is an enlarged view thereof.

FIG. 7 is another bottom plan view thereof.

FIG. 8 is a cross-sectional view thereof.

FIG. 9 is an enlarged view thereof.

FIG. 10 is a top perspective view thereof.

FIG. 11 is a bottom perspective view thereof; and,

FIG. 12 is a side view thereof.

1 Claim, 6 Drawing Sheets
